UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 11, 1925. Serial No. 22,322.

My invention relates to railway traffic controlling apparatus, and particularly to apparatus of the type comprising train carried governing means controlled by energy supplied to the trackway. More particularly, my invention relates to the trackway portion of such apparatus.

I will describe two forms of trackway apparatus embodying my invention, and will then point out the novel features thereof in claims.

In the accompanying drawings, Fig. 1 is a diagrammatic view showing one form of trackway apparatus embodying my invention; and Fig. 2 is a view showing a modified form of the apparatus illustrated in Fig. 1, and also embodying my invention.

Similar reference characters refer to similar parts in both views.

Referring first to Fig. 1, the reference characters 1 and 1^a designate the track rails of a stretch of railway track over which traffic normally moves in the direction indicated by the arrow. These track rails are divided, by means of insulated joints 2, into a plurality of successive track sections A—B, B—C, C—D, etc.

A trackway signal, here designated by the reference character S with an appropriate exponent is provided for each track section. As here shown, each signal is of the three position semaphore type capable of displaying a proceed, a caution, or a stop indication, and is located adjacent the entrance end of the associated section, but this particular form and location are not essential. These trackway signals S are controlled by means forming no part of the present invention and therefore omitted from the drawing for the sake of simplicity. For purposes of the present disclosure it is sufficient to state that each signal is so controlled that when the associated section is occupied the signal indicates stop, when the associated section is unoccupied and the section next in advance is occupied the signal indicates caution, and when the associated section and the section next in advance are both unoccupied, the signal indicates proceed.

Associated with each signal S is a pole changer designated by the reference chara-

ter P with an exponent corresponding to the location, and arranged to occupy one position when the signal indicates stop and to occupy a different position when the associated signal indicates proceed or caution.

Each track section is provided with a source of alternating track circuit current. As here shown the immediate supply of such current is the secondary 10 of a track transformer designated by the reference character T with an appropriate distinguishing exponent. The secondary 10 of each such transformer T is connected, through the usual impedance 11, across the rails adjacent the exit end of the associated track section.

Associated with each track section is a line transformer designated by the reference character H with an exponent corresponding to the location, and having its primary winding 20 constantly supplied with alternating current from some convenient source, such as an alternator M, over line wires 3 and 3^a. The secondary 19 of each line transformer is directly connected, through the associated pole changer P, with the primary 12 of the adjacent track transformer T. It follows therefore that each track section is supplied with alternating track circuit current of one relative polarity, which I shall term "normal" relative polarity, when the signal for the section next in advance indicates caution or proceed, and of the other relative polarity, which I will call "reverse" relative polarity, when such signal indicates stop.

Each track section is further provided with a track relay designated by the reference character R with an exponent corresponding to the location. Each such relay comprises two windings, 13 and 14, one of which, 13, is connected with the rails adjacent the entrance end of the associated section. The remaining winding, 14, of each track relay R is constantly supplied with alternating current from secondary 19 of the adjacent line transformer H. When winding 13 of any relay R is supplied with alternating current of normal relative polarity, the contacts 22 and 27 on such relay are swung into their right hand or normal positions. When winding 13 is supplied with current of reverse relative polarity the contacts move to their left hand or reverse

positions, and when the supply of current to either of windings 13 or 14 is interrupted, the contacts assume an intermediate position, closing their "back" contacts.

5 Means are also provided for supplying each track section with loop current, which, as shown in the drawing, flows through the two rails of the section in parallel. For this purpose I provide each track section 10 with an impedance 4 connected across the rails adjacent the entrance end of the section, and a similar impedance 9 connected across the rails adjacent the exit end of the section. Two other impedances 7 and 8 are 15 connected across the rails at an intermediate point in the section, and still another impedance 6 is connected across the rails at a point intermediate the entrance end of the section and the point of connection of impedances 7 and 8.

20 The immediate source of loop current for each section is a loop transformer designated by the reference character L^B with a suitable exponent. The primary 18 of each such loop transformer L^B is constantly supplied with alternating current from secondary 19 of the adjacent line transformer H .

25 Referring particularly to section A—B, loop transformer L^B is provided with two secondaries 15 and 16. The mid point of secondary 16 is constantly connected with impedance 8 in section A—B, through wire 24. When relay R^B is energized in this normal direction the right hand terminal of secondary 16 is connected with impedance 9, over wire 21, normal contact 22 of relay R^B , and wire 23. When relay R^B is energized in the reverse direction the left hand terminal of secondary 16 is connected, through 30 wire 25, reverse contact 22 of relay R^B , and wire 23, with impedance 9. When relay R^B is de-energized, both terminals of transformer secondary 16 are disconnected from the rails. It is therefore plain that the portion of section A—B between impedance 8 35 and impedance 9 is supplied with loop current of one relative polarity which I shall term "normal" relative polarity, when relay R^B is energized in the normal direction, and with loop current of the other, or reverse, relative polarity when relay R^B is energized in the reverse direction. It should also be pointed out that when relay R^B is de-energized the supply of loop current to section 40 A—B between impedances 8 and 9 is interrupted.

45 Secondary 15 of transformer L^B is provided with a circuit which may be traced from the right hand terminal of the secondary, through wire 26, normal contact 27 of relay R^B , wires 28 and 29, impedance 7 in section A—B, through the rails of the section in parallel to impedance 4, thence by wire 30 back to secondary 15. The circuit just traced is provided with a branch from

wire 26, through reverse contact 27 of relay R^B , and wire 31 to wire 29. Section A—B is therefore supplied with loop current of normal relative polarity between the entrance end of the section and impedance 7, when relay R^B is energized in either direction. If, however, relay R^B is de-energized, the circuit just described, and the branch therefor, are opened, and current flows from the right hand terminal of secondary 15 of transformer L^B , through wire 26, back contact 27 of relay R^B , wire 32, impedance 6 in section A—B, through both rails of the section in parallel to impedance 4, thence by wire 30 back to secondary 15. When this circuit is closed loop current of normal relative polarity is supplied to section A—B between impedances 4 and 6. It will therefore be seen that the portion of section A—B between impedances 4 and 7 is supplied with loop current throughout its length, or through a part only of this portion, depending upon the condition of energization of relay R^B .

50 Before explaining the operation of the apparatus as a whole it should be pointed out that the trackway apparatus herein shown and described is suitable for cooperation with train carried governing means forming no part of my present invention and omitted from the drawing for the sake of simplicity. It is sufficient to state that when the stretch of track occupied by the train is supplied with track circuit current and with loop current, both such currents being of normal relative polarity, a proceed indication is received on the train. If the train occupies a stretch of track which is being supplied with track circuit current and also with loop current, the relative polarity of either of which currents is reversed, a caution indication is received on the train. If, however, the supply of either loop current or track circuit current to the stretch of track occupied by the train is interrupted, a stop indication is received on the train.

55 As shown in the drawing the section to the right of point D is occupied by a train indicated diagrammatically at V. Relay R^D is therefore de-energized, and signal S^D indicates stop. Signals S^C and S^B indicate caution and proceed respectively. As a result section C—D is supplied with track circuit current of reverse relative polarity and sections A—B and B—C are supplied with track circuit current of normal relative polarity. Relay R^C is energized in the reverse direction, and relay R^B is energized in the normal direction. It will therefore be seen that loop current of normal relative polarity is supplied to the rails of section A—B throughout the length of the section, and that section B—C is supplied with loop current of normal relative polarity between impedances 4 and 7, and of reverse relative po-

larity between impedances 8 and 9. Section C—D is supplied with loop current of normal relative polarity between impedances 4 and 6, but no loop current is supplied to the rest of this section.

I will now assume that a second train, moving in the direction of the arrow, moves through the stretch of track shown in the drawing. As the train moves through section A—B a proceed indication will be received on the train and this indication will persist after the train enters section B—C. At impedance 8 in section B—C, the reversal of the relative polarity of the loop current causes a caution indication to be received on the train. When the train enters section C—D, this caution indication continues, due to the reversal of the track circuit current in section C—D, the loop current supplied by secondary 15 of transformer L being of normal relative polarity. When the train passes impedance 6 in section C—D, the interruption of loop current causes the train to receive a stop indication which continues throughout the section. Should the second train proceed into the section to the right of point D, a stop indication would still be received due to the shunting of track circuit current by the wheels and axles of the train already occupying this section.

Referring now to Fig. 2, the apparatus shown in this view is the same as the apparatus shown in Fig. 1 except as to the means for supplying loop current to the rails of each section between impedance 4 and impedance 6. In Fig. 2 loop current is constantly supplied to this portion of each section by a transformer Q, the primary 36 of which is connected with the secondary 19 of the associated line transformer H. The secondary 35 of each transformer Q is connected with impedance 4 and with an additional impedance 5 which is located adjacent the impedance 6, this connection being accomplished by wires 33 and 34. Secondary 15 of each transformer L supplies loop current of normal relative polarity between impedances 6 and 7 when the track relay R for the next section is energized in either direction, but not when this track relay is de-energized. In all other respects the apparatus shown in Fig. 2 is the same as that shown in Fig. 1.

As shown in the drawing the section to the right of point D is occupied by a train V. Relay R^P is therefore de-energized. Under these conditions, signal S^C indicates stop, signal S^C indicates caution, and signal S^P indicates proceed. Track circuit current of reverse relative polarity is supplied to section C—D, and track circuit current of normal relative polarity is supplied to sections A—B and B—C. Loop current of normal relative polarity is constantly supplied to each section between impedances 4 and 5

by the associated transformer Q. In addition, section A—B is supplied with loop current of normal relative polarity throughout the rest of the section. Section B—C is also supplied with loop current of normal relative polarity between impedances 6 and 7 and with loop current of reverse relative polarity between impedances 8 and 9.

If a second train should move through the stretch of track shown in the drawing, the train would receive a proceed indication as far as impedance 7 in section B—C, a caution indication between impedance 8 in section B—C and impedance 5 in section C—D, and a stop indication from impedance 5 in section C—D to the train V.

In both Figs. 1 and 2 it will be noted that a proceed indication will be received up to the impedance 7 in the rear of a caution signal, and that a caution indication will be received from such impedance 7 in the rear of a caution signal up to impedance 6 in the rear of a stop signal. This feature is of value where the track sections are so short that it would not be safe to defer a caution indication aboard the train until the train reaches a caution wayside signal.

Although I have herein shown and described only two forms of trackway apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a section of railway track, means for supplying said section with alternating track circuit current of one relative polarity or the other, means controlled by traffic conditions for supplying loop current of one relative polarity or the other to a portion of said section, and means also controlled by traffic conditions for supplying loop current to the remaining portion of such section throughout the portion or to a part only of such portion.

2. Railway traffic controlling apparatus comprising a section of railway track, means for supplying said section with alternating track circuit current of one relative polarity or the other, means controlled by traffic conditions for at times supplying a portion of said section with loop current of one relative polarity and simultaneously supplying another portion of said section with loop current, and for at other times reversing the relative polarity of the loop current supplied to said one portion but not of the loop current supplied to such other portion, and for at still other times discontinuing the supply of such loop currents to both said portions.

3. Railway traffic controlling apparatus

- comprising a section of railway track, means for supplying said section with alternating track circuit current of one relative polarity or the other, means controlled by traffic conditions for at times supplying a portion of said section with loop current of one relative polarity and simultaneously supplying the remaining portion of said section with loop current, and for at other times reversing the relative polarity of the loop current supplied to said one portion but not the loop current supplied to such remaining portion, and for at still other times supplying loop current to a part only of said remaining portion.
4. Railway traffic controlling apparatus comprising a section of railway track, means for supplying said section with alternating train controlling current of one relative polarity or the other depending upon traffic conditions, two sources of loop current for said section, means responsive to traffic conditions for at times supplying loop current of one relative polarity or the other from one said source to the rails of a portion of said stretch, and for at other times interrupting such supply, and means also controlled by traffic conditions for at times supplying loop current from the other said source to an other portion of the section throughout the length of such portion or to a part only of such portion.
5. Railway traffic controlling apparatus comprising two sections of railway track, means for supplying the forward section with alternating track circuit current of one relative polarity or the other depending upon traffic conditions, a relay responsive to reversals of the relative polarity of such track circuit current, means controlled by said relay for supplying a portion of the rear section with loop current of one relative polarity or the other depending upon the condition of said relay, and means for supplying the remaining portion of the rear section with loop current throughout the length of such portion or to a part only of such portion depending upon the condition of said relay.
- 50 6. Railway traffic controlling apparatus comprising two sections of railway track, means for supplying the forward section with alternating current of one relative polarity or the other depending upon traffic conditions, a relay responsive to reversals of the relative polarity of such track circuit current, a first transformer secondary having its mid point constantly connected with the rails at a first intermediate point in the rear section, means including a normal contact of said relay for connecting one terminal of said first secondary with the exit end of such rear section, means including a reverse contact for connecting the remaining terminal of said first secondary with the exit end of said rear section, a second transformer secondary having one terminal constantly connected with the rails adjacent the entrance end of said rear section, means including a normal contact and a reverse contact of said relay in parallel for connecting the remaining terminal of said second transformer secondary with the rails adjacent said first intermediate point, and means including a back contact of said relay for connecting such remaining terminal of said second transformer secondary with the rails adjacent a second intermediate point in said rear section, such second intermediate point being located between the entrance end of the rear section and said first intermediate point.
7. Railway traffic controlling apparatus comprising a track divided into a plurality of sections, means for supplying alternating track circuit current of normal or reverse relative polarity to the rails of each section according as the section next in advance is unoccupied or occupied, means for constantly supplying alternating loop current of normal relative polarity to the rails of each section from the entrance end of the section to an intermediate point in the section, means for supplying alternating loop current of normal relative polarity to the rails of each section from said first intermediate point to a second intermediate point in the section when the section next in advance is unoccupied but not when the section next in advance is occupied, and means for supplying alternating loop current to each section from said second intermediate point to the exit end of the section when the next section in advance is unoccupied but not when the next section in advance is occupied said last mentioned loop current being of normal or reverse relative polarity according as the second section in advance is unoccupied or occupied.

In testimony whereof I affix my signature.

ROBERT M. GILSON.
